TOE CLAMP FOR SKI BINDING

Bernard E. Berlenbach, 15 Middle Court,
Mill Valley, Calif. 94941

Filed Dec. 28, 1967, Ser. No. 9,961

Term of patent 14 years

(Cl. D34—14)

FIG-1

FIG-2

FIG-3

FIG-5

FIG-4

FIG-6

FIGURE 1 is a side, top and front perspective view of a toe clamp for ski binding, showing my new design;

FIGURE 2 is a side elevational view, the opposite side being substantially a mirror image thereof;

FIGURE 3 is a front elevational view thereof;

FIGURE 4 is a rear elevational view;

FIGURE 5 is a top plan view; and

FIGURE 6 is a bottom plan view thereof.

I claim:

The ornamental design for a toe clamp for ski binding, as shown and described.
